UNITED STATES PATENT OFFICE.

GEORGE W. BEADLE, OF NEW YORK, N. Y., ASSIGNOR TO THE SINGLE SERVICE PACKAGE CORPORATION, OF NEW YORK, N. Y., A CORPORATION OF NEW JERSEY.

PAPER VESSEL.

1,203,569.

Specification of Letters Patent. Patented Nov. 7, 1916.

Application filed September 27, 1915. Serial No. 52,927.

To all whom it may concern:

Be it known that I, GEORGE W. BEADLE, a citizen of the United States, residing at New York city, in the county of New York and State of New York, have invented certain new and useful Improvements in Paper Vessels; and I do hereby declare the following to be a full, clear, and exact description of the invention, such as will enable others skilled in the art to which it appertains to make and use the same.

This invention relates to liquid tight paper vessels, and has for its object to provide a vessel which will be more efficient in service for the purpose intended than those heretofore proposed.

With these and other objects in view the invention consists in the novel details of construction constituting the vessel, all as will be more fully hereinafter disclosed and particularly pointed out in the claims.

In order that the invention may be more clearly understood attention is directed to my U. S. Patent No. 1,133,425 dated March 25 30th, 1915, entitled machine for closing paper cartons in which suitable mechanism is disclosed for producing the vessel. As will be clear from said patent, it is well known that in the closing of paper vessels that are 30 designed to hold liquid it is essential that an exceedingly tight closure be formed because otherwise owing to the nature of the material and to the subsequent compression of the liquid filled package during handling, 35 the contents are liable to leak out and thereby destroy the efficiency of the package.

In order to provide an exceedingly inexpensive and at the same time a very efficient closure for the vessels I have devised a disk 40 which is slightly larger than the interior of the mouth of the vessel to be closed, and I force the said disk into the bottle mouth without raising a bur on the outer rim of the disk and otherwise form an exceedingly 45 tight and efficient closure which gives perfect satisfaction in practice, all as will be more clearly disclosed hereinafter.

Referring to the accompanying drawings forming a part of this specification, in which 50 like numerals designate like parts in all the views—Figure 1 is a diagrammatic sectional view illustrating one means of inserting the disk into the vessel body; Fig. 2 is a diagrammatic sectional view showing the

disk after it has been inserted into the vessel body and the beginning of the grooving operation; Fig. 3 is a diagrammatic view illustrating the completed closure formed by the operations indicated in Figs. 1, and 2; Fig. 4 is a diagrammatic sectional view 60 illustrating a modified means and method of inserting the disk into the vessel body; and Fig. 5 is a sectional view of a vessel formed from the procedure indicated in Fig. 4:

1 indicates any suitable paper vessel body, 65 preferably of the spirally wound type, 2 any suitable mandrel inside the body 1 and provided with the dished or curved extreme end 3, together with the groove 4 surround-
ing said end 3.

5 indicates any suitable plunger provided with the expanding plunger member 6, hav-
ing the extreme edge 7 adapted to tightly
fit the interior 8 of the vessel body 1 and to
force the extreme edge of the closing disk 9 75
into the body 1 without raising a bur thereon.

10 represents a spring-pressed plunger as-
sociated with the plunger 5 and expanding
member 6, in order to tip the disk 9 and
thereby enable it to readily enter the body 80
portion 1 all as will be clear from my said
patent above.

The disk 9 being tipped as indicated in
Fig. 1, and the extreme edge 7 of the mem-
ber 6 closely fitting the interior 8 of the said 85
body 1, upon causing a relative movement
between the said member 6 and mandrel 2
the said disk 9 is firmly and smoothly forced
into the interior of the body 1 and jammed
tightly against the curved or dished portion 90
3 of the mandrel 2, all as will be clear from
Fig. 2. In order to more effectually jam the
disk 9 into its proper position, while forcing
the extreme edges of the disk home, I pro-
vide the plunger 5 with an outwardly curved 95
or partially spherical surface 11 which is
adapted to substantially fit the curved por-
tion 3 of the mandrel 2 so that the disk 9 is
jammed tightly between the surfaces 3 and 11
and its edges are firmly and tightly jammed 100
in place against the interior wall 8 of the
body 1. After the disk is thus forced home
the package is subjected to the action of a
crimping tool, which turns over the extreme
edges 16 of the body 1 and crimps them 105
tightly against the disk 9, all as will be clear
from Figs. 2 and 3. After this crimping
action has taken place, and before the man-

2. drel is withdrawn, the body 1 is subjected to the action of a grooving tool 13 which forms in the said body 1 immediately beneath the disk, a groove such as 15, so that 5 the extreme edges 17 of the disk 9 are firmly held between the said groove 15 and the said crimped over edge 16 of the body 1. The disk being thus larger than the interior diameter of the body 1 and the material of the 10 said body being of the spirally wound character and containing considerable quantities of glue the said material is more or less soft and pliable, and therefore as it dries it shrinks very materially, and causes the outer 15 portion of the body 1 just opposite the edges 17 of the disk to bulge outwardly to form the circumferential bead 18 which is shown in a somewhat exaggerated form in the various figures. That is to say, when the disk 20 is first placed inside the body portion 1 and the edge 16 crimped over in place, the material may be very slightly bulged outward as indicated at 19, on the top side of Fig. 2, and when the grooving tool 13 forms the 25 groove 15 in the said body 1 this bulging action is somewhat increased as is indicated at 20 in Fig. 2, and when the material of the body 1 dries it shrinks to such an extent that the said bulging bead 20 is somewhat increased as is indicated at 18 in Fig. 3. The 30 result of these various operations as is fully disclosed in my said patent above is to provide an exceedingly tight and strong joint which will effectually withstand commercial 35 handling while the packages contain liquid, and in fact produce a paper vessel having an exceedingly long life and very durable for the handling of milk, oysters, butter, and liquids of all kinds. To facilitate the use of 40 the vessel and to prolong its life it is treated with the usual paraffin bath, all as is familiar to those skilled in the art.

It will be observed that the vessel closed 45 as above is provided with an inwardly curved disk such as 9 so that the interior strain of the vessel tends to still further enlarge the disk and to tighten the joint. In use these curves are often flattened out, so that the disk appears quite flat, although when the 50 strains are not very great upon the disk the curved feature remains.

In the slightly modified form of the invention illustrated in Figs. 4 and 5, the disk is not curved when locked in position. According 55 to this modified form of the invention a grooved rib or annular shoulder 25 is first formed in the vessel 1 by any suitable and well known means whereupon the disk 9 slightly larger than the interior 8 of the 60 vessel is brought to place in a manner best disclosed in my former Patent No. 1,125,041 dated Jan. 19, 1915, entitled carton capping machine from which said modified form of the invention is derived. The disk 9 being 65 thus brought in place the pivoted spring-

pressed circular member 26 presses thereon, and the pushing edges 27 of the plunger 28 fits accurately the interior diameter of the protecting ring 29, and forces the extreme edges 270 of the disk down past the shoulder 70 of said ring against which rest the extreme edges of the body 1, and into its position on top of the annular rib or shoulder 25 of the vessel. In this form of the invention the body 1 being held as indicated in my said 75 Patent No. 1,125,041 or otherwise held, may be subjected to the action of any suitable crimping machine and the upper edge 30 of the body 1, crimped down in position as illustrated in Fig. 5 whereupon the said disk 9 80 is firmly locked in place. During this crimping action a mandrel may be inserted in the body 1 as is indicated in Fig. 1 or if the other end of the body 1 is already closed said mandrel of course would be omitted. 85 The material of the body 1 being likewise softened by glue or by other means it will upon drying appreciably contract and thus cause the extreme edges 27 of the disk to force outwardly the said material and to 90 thereby form the annular exterior bead 31 which is shown somewhat exaggerated in Fig. 5.

It will thus be seen that in both forms of the invention I am enabled to make an exceedingly liquid tight joint by first forcing 95 inside the paper body portion of the vessel a disk slightly larger than the interior diameter thereof, say about one thirty second of an inch larger than said diameter and by 100 forcing the disk firmly against a mandrel.

It will further be seen that the disk in both forms of the invention is forced home without any bur being formed on its exterior edges, owing to the fact that the forcing members 6 and 27 closely fit the interior 8 of the paper vessel 1. The extreme edge of the said paper vessel is preferably protected in both cases by means of a ring such as the member 39 shown in my said 110 Patent No. 1,133,425 or such as the ring 29 illustrated in Fig. 4 of this application. This closure will be distinguished from other closures that have heretofore been employed and which do not employ in their 115 make up disks of a diameter larger than the interior of the vessel to be closed. Said former closures employ a disk either of the same diameter as the interior of the vessel or else they employ a closure slightly 120 smaller than the interior of the vessel. The result is when such closures are employed for the shipping of milk for example, over long distances, or wherein the said packages are severely handled, they invariably leak, 125 whereas my closures do not.

It is obvious that those skilled in the art may vary the details of construction, as well as the steps of procedure without departing from the spirit of the invention and there- 130

fore I do not wish to be limited to the above disclosure except as may be required by the claims.

What I claim is:

- 5 1. A vessel having a paper body portion provided with an exterior bead, an interior bead, a disk larger than the interior of said vessel fitting the interior of said first named bead, said disk contacting with and overlying said interior bead, and the extreme edge portion of said vessel being turned in, disposed parallel to said body portion, and crimped down against the outer face of said disk to lock it securely against said interior bead, substantially as described.
- 10 2. A paper body portion of a tubular form provided with a closure comprising a disk

larger than the interior of said body portion; the extreme edge of said body portion being turned over and crimped down parallel to said body portion against one face of said disk; the material of said body portion being forced inward on the other side of said disk to form an annular locking shoulder; and the material of said body portion being forced outwardly to form an exterior bead in which said disk rests, substantially as described. 20 25

In testimony whereof I affix my signature, in presence of two witnesses.

GEORGE W. BEADLE.
